UNITED STATES PATENT OFFICE.

ALFRED S. McCASKEY, OF CHICAGO, ILLINOIS.

PRINTING-TELEGRAPH.

1,005,862.

Specification of Letters Patent.

Patented Oct. 17, 1911.

Application filed May 3, 1901, Serial No. 58,646. Renewed December 22, 1909. Serial No. 534,551.

To all whom it may concern:

Be it known that I, ALFRED S. McCASKEY, a resident of Chicago, Illinois, have invented a new and useful Improvement in Printing-Telegraphs, which invention is fully set forth in the following specification.

This invention has general reference to electrical signaling or communication and relates more particularly to printing telegraph systems, though it will be understood from the drawings and the description thereof, that the principal features of the invention and much of the apparatus hereinafter described, are applicable to many different industrial uses, and may be employed wherever it is desired to produce by electrical impulses distinct mechanical effects. In the following description, therefore, the designation of distinct functions to certain parts 20 of the apparatus and specific names applied to parts of the apparatus are not to be considered as limitations, but are merely used for convenience in describing the apparatus shown and its operation with respect to printing telegraph systems.

Referring in general terms to the organized apparatus herein illustrated as embodying the several features of my invention, said apparatus embraces a transmitter provided, preferably, with a key board like a typewriter and which, upon the actuation of a particular key, transmits a series of electrical impulses representing the character appropriated to that key. Said impulses 35 are collected by suitable devices located at the transmitting station and sent out to line. The manipulation of each key transmits a certain number of impulses, some of which are of one polarity and some of the other 40 polarity, and each character to which one of the keys of the transmitter is appropriated, is distinguished from all other characters by a particular permutation of the impulses. These impulses, which are collected and sent 45 to line, act upon the receiving mechanism at the receiving station.

The electrical currents by which the impulses are transmitted may be all of one polarity, but it is preferred to use reversals 50 of current in connection with multiple sets of pole changers, five or more in each set, which are connected with a main battery circuit at the transmitting station, and so located with respect to parts operated by the 55 keys that the normal position of one or more of the pole changers of each set is changed

by the depression of each key lever. Each pole changer of each set operates in connection with a pair of terminals, one terminal of each pair being connected with one pole 60 of a divided main circuit battery, and the other terminal with the other pole thereof. The pole changers are normally in contact with the positive terminals. The pole changers of each set are electrically connected with the insulated segments of a collecting device, by which the impulses are collected and sent out to line. Eight sets of pole changers are herein illustrated. All of 65 said sets of pole changers are placed in the path of rotation of an arm which is moved successively into relation therewith by parts operated by key levers, whereby, upon depression of one of the key levers, one or more of the pole changers of one set is shifted to 70 its negative terminal, so that when the main circuit is closed through this particular set, one or more of the impulses sent out to line will be negative while the others will be positive. Associated with the several sets of 75 pole changers is a single ground terminal which is connected with the main line and associated with said ground terminal is a vibratory lever which is connected with the collector above mentioned and through 80 which, when said lever is in contact with the ground terminal, the collected impulses are sent out to line.

The collector consists of a circular disk provided with a number of sets of insulated 85 segments equal to the number of sets of pole changers, each set of segments having a number of segments equal to the number of pole changers in each set, and the pole changers of each set being connected with 90 the segment of the corresponding set. A rotary arm carried by a central rotary shaft of the collector moves successively over said segments, said arm being rotated by an escapement mechanism operated by a local 95 relay circuit of the main line. Said arm is provided with a tail piece which moves successively over an inner ring divided into a number of insulated segments corresponding to the number of the sets of pole changers. 100 The segments of said inner ring are connected with the oscillatory levers associated with the ground terminal and when either of said levers is in contact with the ground terminal, a circuit from the main battery is 105 closed to one set of the pole changers, the segments on the disk connected therewith,

the rotary arm and its tail piece, the inner segment in contact with the tail piece, and said ground terminal to the line wire.

By the arrangement of the pole changers 5 and the collecting devices described, the operation of the key board is made independent of the working of the line. This is accomplished as follows: As the rotary arm, associated with the pole changers, comes to 10 rest over each set of pole changers and a key depressed, a permutation is made thereby to correspond with the permutation of impulses to be sent to line. After such permutation is made the ground terminal is 15 closed to line. It is of no consequence that the permutation set up by these pole changers be sent out to line at once in the form of impulses of different polarity, as said pole changers will remain in their relative 20 positions until the rotative arm thereover has completed one revolution. Therefore, the impulses from each set of pole changers may be sent out to line during any time covering one period of complete rotation of 25 said arm. Means are provided for restoring the pole changers before the arm is again brought to rest thereon. The rotary arm of the collector will be adjusted to have a uniform speed of rotation and practically 30 as great as the average speed of the operator, including the necessary pauses in the work of the operator and it matters not if the operator manipulates the keys in advance of the operation of the line so long 35 as the permutation set up in each set of pole changers are sent out in the form of impulses before the rotary arm again reaches that particular set of pole changers. The operation of the line, therefore, is uniform 40 and the line need not be idle at any time although the operation of the keys may be intermittent. I am, therefore, enabled to provide a uniform and practical length of time for sending the impulses out to line, 45 and for the operation of the receiving apparatus. Any suitable receiving mechanism may be used with said transmitting device, the same preferably embracing a distributor, a selector and a printing device, the 50 distributor distributing the impulses to the selector wherein they are translated into a definite mechanical effect and which mechanical effect may operate a typewriter, type wheels or other device. Preferably the 55 receiving mechanism which is employed is that described and claimed in my application Serial Number 534,482, filed December 22d, 1909, the same being a division of my application Serial Number 58,646, filed 60 May 3, 1901.

In the drawings:—Figure 1 is a plan view of the transmitting device. Fig. 2 is a central vertical section of the mechanical parts of said transmitting device. Fig. 3 is a plan view of a fragment of the parts 65

shown in Fig. 2 with some of the key levers broken away. Fig. 4 is a cross section on line 4—4 of Fig. 3. Fig. 5 is a transverse, vertical section on line 5—5 of Fig. 6. Fig. 6 is a horizontal, plan section on line 6—6 of Fig. 5, with the key levers broken away. Fig. 7 is a view showing in detail one set of pole changers and the arm which carries the devices for shifting the pole changers, and Fig. 8 is a similar view with some of the parts in changed positions. 75

I will refer now in detail to the construction of the transmitting apparatus located at the transmitting station in connection with the drawings. The transmitting apparatus is provided with a suitable base A upon which the principal parts of the transmitting device are mounted. B B are a plurality of key levers which are provided with keys b. Said key levers are pivoted 80 at their rear ends upon a transverse rod A¹ mounted in the upper ends of frame plates or standards A² at each side of the base. C C designate a plurality of other levers, below the levers B pivoted upon a transverse rod A³ mounted in the frame pieces A in advance of the rod A¹. The rear ends of said levers C carry a plurality of raised bars C¹. Each lever B is provided with one or less than five depending pins or studs b¹ 85 adapted to engage said cross bars C¹ so that when a key B is depressed, one or more of the keys C will be also depressed. The levers C are divided into two sets, each set containing five levers. The forward ends of said levers C are connected with five concentric rings D located in the same plane, one set of said levers being connected with the rings at one side of the center thereof, and the other at the other side of said center. Supported on said base A, below the rings D, are a plurality of radially arranged plates E which carry on their upper margins a plurality of sets of insulated terminals e e¹, there being five pairs of such 90 terminals in each set. One of said terminals of each set is positive and the other negative. Pivoted to said plates E to vibrate in vertical planes and insulated from the plate, are a plurality of pole changers e² which have their upper ends located between the terminals e e¹. Said pole changers e² normally rest in contact with the positive terminals e and are adapted to be 95 swung into contact with the negative terminals e¹ by means of plungers F carried by a radial rotary arm F¹, which latter is connected with and rotates about a central post or standard F² mounted on the base plate A. The pins F are spring pressed and are each under one of the rings D and over one of the pole changers when the arm is 100 brought to a rest, so that when one or more of the rings are depressed by the depression of one of the key levers, in the manner above 105 110 115 120 125 130

indicated, one or more of said pins will be depressed and will engage one or more of the pole changers e^2 to throw the same into contact with the negative terminals. For this purpose the meeting ends of the pins and levers are tapered as clearly shown in Fig. 2.

As herein shown, eight sets of pole changers are provided. All of the positive terminals of the pole changers are connected by wire 1 with one pole of a divided battery 2, and all the negative terminals are connected with the other pole of said battery by a wire 3. The pole changers e^2 of each set are connected by wires 4 with a like number of insulated segments g of a collector disk G , there being as many sets of segments as sets of pole changers and the number of segments in each set being equal to the number of pole changers in each set.

F^4 is a ground terminal which is mounted on the post F^2 and insulated therefrom, and e^3 is a switch lever, one for each set of pole changers, adapted to be swung into contact with the ground terminal. Said ground terminal is connected with the line wire 5.

G^2 is a rotary arm mounted on the collector shaft g^1 concentric with the annular series of the segments g . The outer end of the lever passes successively over said segments. Said arm is provided with a tail piece which moves in contact with a ring G^1 concentric with the shaft g^1 and consisting of a number of insulated segments equal to the number of sets of pole changers. Each of the segments of the ring G^1 is connected by a wire 6 with one of the switch levers e^3 . When the lever e^3 contacts with the ground terminal F^4 the circuit is closed through the battery 2, one set of the pole changers, the segments g , the lever arm G^2 , one segment of the ring G^1 , wire 6 and ground terminal F^4 and out to line 5. The line wire 5 passes through the coils of a relay H , which operates a local circuit, including a magnet H^1 and battery H^2 , the magnet operating an escapement lever H^3 which actuates an escapement mechanism for turning the arm G^2 step by step, said escapement mechanism being substantially like the escapement mechanism for the distributor hereinafter to be described.

The arm F^1 is adapted to be rotated step by step as the keys are depressed, and its position of rest is always over one set of the pole changers. Said arm is given a step by step movement by the following mechanism: f designates a ratchet wheel which is rigid with a shaft on which the arm is mounted. Said wheel is adapted for engagement by a pawl f^2 carried upon the lower end of a vibrating lever F^3 . The upper end of said lever is connected with a jointed lever A^4 below the base, the other

end of said jointed lever being connected rigidly with the base. Connected with said jointed lever at the joint thereof is a spring pressed, vertically, reciprocatory bar A^5 which is pivoted at its upper end to a transverse universal bar A^6 , extending beneath the forward ends of all of the key levers B and adapted for contact with pins b^2 depending from all of said levers, whereby upon depression of either of the key levers B , the pawl and ratchet mechanism is operated to move the arm F^1 one step, or from one set of pole changers to the other.

The arm F^1 is provided on its under side in advance of the plungers F with a plurality of cam projections f^3 whose office it is to restore the pole changers to the positive terminals just before the arm stops thereover. Said arm is also provided with another cam projection f^4 located in the rear of plungers F and adapted, after certain of the plungers F have moved certain of the pole changers into contact with their negative terminals, to swing the switch lever e^3 against the ground terminal and close the circuit to the line through said terminal. In order to open the line circuit to each of the sets of pole changers the plungers are brought to rest thereover in the next rotation of the arm, the lever F is provided with a forwardly projecting cam arm f^5 which swings the lever e^3 of each set out of contact with the ground terminal just before the arm F^1 is brought to rest over said set in the manner indicated in Fig. 8. It will be seen, therefore, that after one or more pole changers of each set has been shifted in the manner described into contact with their negative terminals, the circuit is closed to the corresponding segments on the disk G and remains closed during almost the entire subsequent rotation of the arm F^1 , in which time the arm G^2 of the collector passes over the corresponding segments and sends the permuted impulses to the line.

What I claim is:

1. In a telegraph-system, a key board transmitter having two or more sets of pole-changers acted on successively by the keys, and means for bringing the sets of pole-changers into connection with the main line subsequent to the operation by the keys.

2. In a telegraph-system, a keyboard transmitter having a plurality of sets of pole-changers, actuating mechanism for the pole-changers controlled by the keys, and means for bringing the sets of pole-changers into connection with the main line and subsequent to the operation thereof by the aforesaid actuating mechanism.

3. The combination with the signaling keys, of a plurality of sets of pole changers, means, controlled by the keys, for acting successively upon the several sets and shift-

- ing certain of the pole-changers therein, and a collector independent of the operation of the keyboard for sending impulses to line from the several sets of pole-changers 5 successively.
4. The combination with the signaling keys, of a plurality of sets of pole-changers, means for bringing the sets of pole changers successively into operative connection 10 with the keys, and a collector operated independently of the operation of the keys for connecting the sets of pole-changers successively with the line.
5. The combination with the signaling keys, of a plurality of sets of pole-changers, an actuating device therefor controlled by the keys and movable into operative relation with said sets successively, and a collector for connecting said sets successively with 15 the line.
6. In a telegraph system, a keyboard transmitter wherein the movement of any key shifts the pole-changers of a set in accordance with a predetermined permutation, 20 having in combination two or more sets of pole-changers, and means for bringing said sets successively into operative relation with the key-board.
7. The combination with the signaling keys of a plurality of sets of pole-changers, a rotatable actuating device therefor, means for moving said device into operative relation with the several sets successively, and a collector for connecting the several sets 25 successively with the main line.
8. The combination of the signaling keys, a plurality of sets of pole-changers, means for actuating the pole-changers of the several sets respectively, means for restoring 30 the pole-changers to their normal position between successive operations thereof, and means for connecting the several sets successively with the line.
9. In a telegraph system, a key-board transmitter wherein the movement of any key shifts the pole-changers of a set in accordance with a predetermined permutation, having in combination two or more sets of pole-changers, means for bringing the sets 35 successively into operative connection with the keys, and means for shifting the pole changers of each set to their normal position before they are brought under the action of the keys.
10. In a telegraph system, a key-board transmitter having a plurality of pole-changers acted on successively by the keys, an actuating device for such pole-changers, a collecting device, and means associated 40 with said actuating device and operative to bring said collecting device into circuit with said pole-changers.
11. In a telegraph system, a key-board transmitter having a plurality of pole 45 changers acted on successively by the keys,
- a collecting device, and means for bringing the pole changers into circuit with the collecting device whereby the impulses are sent to line.
12. The combination with the signaling keys, of a plurality of sets of pole-changers, a rotating arm movable above said pole-changers, a plurality of spring-pressed plungers carried by said arm, means operating said plungers according to a predetermined permutation upon the depression of a key, and a collector for connecting the several sets successively with the main line. 70
13. The combination with the signaling keys, of a plurality of sets of pole-changers, a rotating arm movable above said pole-changers, a plurality of spring-pressed plungers carried by said arm, means operating said plungers according to a predetermined permutation upon the depression of a key, a collector for connecting the several sets successively with the main line, and means carried by said arm and operative to move the pole-changers into engagement 75 with the positive terminals. 80
14. The combination with the signaling keys, of a plurality of sets of pole-changers, a rotatable actuating device therefor, means operative upon the depression of a key for moving said device into operative relation 85 with the several sets successively, and a collector for connecting the several sets successively with the main line. 90
15. The combination with the signaling keys, of a plurality of sets of pole-changers, a rotatable actuating device therefor, lever mechanism operative upon the depression of a key for moving said device into operative relation with the several sets successively, and a collector for connecting the several 95 sets successively with the main line. 100
16. The combination with the signaling keys, of a plurality of sets of pole-changers, a ground terminal connected to the line wire, a collector for connecting the several sets of pole-changers successively with the main line, a switch associated with each set of pole-changers and connected to said collector, and means moving one of said switches into contact with said terminal to 110 close the circuit through the set of pole-changers associated with said switch. 115
17. The combination with the signaling keys, of a plurality of sets of pole-changers, actuating mechanism therefor, a ground terminal connected to the line wire, a collector for connecting the several sets of pole-changers successively with the main line, a switch associated with each set of pole-changers and connected to said collector, and means associated with said actuating mechanism operative to engage one 120 of said switches with said terminal to close the circuit through the set of pole-changers associated with said switch. 125
18. The combination with the signaling keys, of a plurality of sets of pole-changers, actuating mechanism therefor, a ground terminal connected to the line wire, a collector for connecting the several sets of pole-changers successively with the main line, a switch associated with each set of pole-changers and connected to said collector, and means associated with said actuating mechanism operative to engage one of said switches with said terminal to close the circuit through the set of pole-changers associated with said switch. 130

18. The combination with the signaling keys, of a plurality of sets of pole-changers, a rotating mechanism actuating the same, a ground terminal connected to the line wire, a collector for connecting the several sets of pole-changers successively with the main line, a switch associated with each set of pole-changers and connected to said collector, means carried by said mechanism engaging one of said switches with said terminal to close the circuit through the set of pole-changers associated with said switch, and means carried by said mechanism for disengaging said switch and terminal.
- 15 19. The combination with the signaling keys, of a plurality of sets of pole-changers, a rotatable actuating device, a plurality of plungers carried thereby and operative to engage said pole-changers, a plurality of 20 concentric rings arranged above said plungers, a plurality of key levers, and con-

nnections between said levers and rings whereby the depression of a key shifts the pole-changers of a set in accordance with a predetermined permutation.

25

20. The combination with the signaling keys, of a plurality of sets of pole-changers, a rotatable actuating device, a plurality of plungers carried thereby and operative to engage said pole-changers, a plurality of 30 concentric rings arranged above said plungers, a plurality of pivoted levers connected to said rings, a plurality of key levers, and connections there-between and said first-mentioned levers.

35

In testimony whereof I have signed this specification in the presence of two subscribing witnesses.

ALFRED S. McCASKEY.
